UNITED STATES PATENT OFFICE.

GEORGE LOWDEN, OF BROOKLYN, NEW YORK.

IMPROVEMENT IN TREADLES FOR SEWING-MACHINES.

Specification forming part of Letters Patent No. 126,889, dated May 21, 1872.

To all whom it may concern:

Be it known that I, GEORGE LOWDEN, of the city of Brooklyn, in the county of Kings and State of New York, have invented a new and useful Improvement in the Mode of Operating Sewing-Machines; and I hereby describe in what manner the same is to be constructed, arranged, and operated. The accompanying drawing is lettered to correspond with and form a part of the specification, which sets forth in a full, clear, and exact manner my said invention; and in order that the public may fully understand the nature thereof, I will describe it as follows, to wit:

Figure 1 is a front elevation of the supporting frame-work *f* of a sewing-machine, the upper parts having been removed in order to show more clearly the individual parts of my invention, which are arranged upon the driving-shaft *S* of the machine. *A* and *A'* are two arms, which are secured to and vibrate with the treadle-bar *N* when operated by the treadles *T T'*. The arm *A* stands at about ninety degrees, having its tapering top end attached to the end of the band *O*, which passes one or more times around the larger drum *D* upon the left-hand end of the shaft *S*, which is also provided with a grooved band-wheel, *B*, which operates the needle-bar upon the top of the table. *F* is a vertical section of an ordinary fly-wheel, which may be placed at any suitable locality upon the driving-shaft *S*, or dispensed with altogether, if preferred. The short arm *A'* is elevated at an angle of about fifteen degrees, with its tapering point fastened to the end of belt or band *O'* that is secured to and passes one or more times around the outer periphery of the smaller drum *D'* upon the right-hand end of the driving-shaft *S*. The drums *D D'* are secured to the reels or smaller drums, upon which the flat-wound springs *W W'* are secured to communicate motion to the drums *D D'*, the vibrating bars *A A'*, and bands *O O'*, when operated by the treadle-bar *N* by means of the treadles *T T'*. The loose ends of springs *W W'* are held in position by means of pins *U U* passing through the frame *f*.

Fig. 2 is a vertical end view of a section of the drum *D'*, cut through the center thereof in order to show the ratchet *R* secured upon the shaft *S*, so that the same will be operated by the pawl *P*, which is secured upon a pin riv-

eted or screwed into one of the heads or vertical side of the drum *D'*, which oscillates freely with the spring-reel *W'* upon the shaft *S* by the movement of the arm *A'*, which causes the band *O'* to operate the drum *D'*, so that the pawl *P* will operate the ratchet *R* and shaft *S*. When the arms *A* and *A'* stand in the position shown in dotted lines at *a a'*, the pawl *P* will also be dropped in the position shown in dotted lines at *P'*. The larger cylinder *D* is shown in this figure by a single circle. This drum is also operated around the shaft *S* and provided with a ratchet and pawl similar to *D'*. The wound springs *W W'* are operated alternately to prevent the band *O* from getting too slack, as well as assisting the operator to work the treadle-bar *N*, by alternately drawing back the arms *A A'* as it (the spring) in each drum unwinds after the pawl *P* is set free or dropped down upon the bottom side of the drum'; and when the spring *W* is relaxed the spring *W'* is at its greatest tension; hence the machine cannot be stopped upon a dead-center, and the use of the crank-motion is dispensed with to operate the shaft *S* by the alternate pressure of the heel and toe upon the treadles *T T'*, by which means the arms *A* and *A'* put the drums and flat-wound springs in motion.

Fig. 3 is an enlarged section of one-half of the drum *D*, showing the construction of the ratchet *R*, which is made in three sections screwed or bolted together. The middle section *L* may be either leather, hardened rubber, or wood covered with rubber or any other non-conductor of sound; and this section *L* projects beyond the metallic side plates *R R*, so that the pawl *P* strikes the rubber or leather first as it falls into the position shown at *P*, Fig. 2. *W* is a vertical section of the wound spring and reel, which is bolted to the side of drum *D*, so that the drum must oscillate by the action of the spring as well as by the band *O* operated by the arm *A*, Fig. 1.

The advantages of my invention over the present mode of operating sewing-machines are, first, I dispense with the crank-motion usually employed to convert the vertical into rotary motion by the action of the feet upon the treadles; secondly, I give a more uniform easy movement to the working parts of the machine by the application of two oscillating

drums of different diameters, with ratchets R and pawls P, all arranged upon the main shaft S, and operated by the wound springs W, in conjunction with the bands O and vibrating arms A alternately operated by the heel and toe of the operator upon the treadles T T' upon the bar N.

The novelty of my invention is confined to the application and arrangement of the several oscillating devices upon the main shaft and treadle-bar of a sewing-machine, consisting of two drums, D D', of different diameters, with pawls P P and flat-wound springs W W' upon reels, (forming a part thereof,) in combination with the ratchets R secured upon and revolving with the shaft S inside of said drums, to be operated by the bands O O', arms A A', treadle T T' on bar N; therefore,

What I claim as my new and useful improvement, and wish to protect by Letters Patent of the United States, is—

The oscillating drums D D', with wound springs W W' and pawls P P, forming a part thereof, to alternately operate the ratchets R R, which are secured to the shaft S, in combination with the arms A A', flexible belts O O', treadles T T', and bar N, all arranged and operating in the manner substantially as above set forth.

In testimony whereof I hereunto subscribe my name in the presence of two witnesses.

GEORGE LOWDEN.
